UNITED STATES PATENT OFFICE.

THOMAS E. HEETER, OF ST. LOUIS, MISSOURI, ASSIGNOR TO BOORUM & PEASE LOOSE LEAF BOOK COMPANY, OF NEW YORK, N. Y., A CORPORATION OF MISSOURI.

LOOSE-LEAF BINDER.

1,236,560.

Specification of Letters Patent. Patented Aug. 14, 1917.

Application filed August 22, 1913. Serial No. 786,066.

To all whom it may concern:

Be it known that I, THOMAS E. HEETER, a citizen of the United States of America, residing in the city of St. Louis and State of 5 Missouri, have invented certain new and useful Improvements in Loose-Leaf Binders, of which the following is a specification.

The primary object of this invention is to provide improved means for swinging a 10 locking element to and from the binder posts.

Another object is to provide an improved locking element for binder posts.

Other and further objects will appear in 15 the specification, and be specifically pointed out in the appended claims, reference being had to the accompanying drawings exemplifying the invention, and in which,

Figure 1 is a fragmentary plan view of a 20 portion of the top cover, showing this improved device applied thereto.

Fig. 2 is a horizontal section of this improved device showing its introduction against a pair of binder posts on a bottom 25 cover before the locking elements have locked against the posts.

Fig. 3 is an enlarged horizontal section of a portion of this improved device showing one of the locking elements in locking position with one of the binder posts.

Fig. 4 is an enlarged longitudinal section taken on the line IV—IV, Fig. 3.

Fig. 5 is an enlarged cross section taken on the line V—V, Fig. 3.

Referring to the accompanying drawings: 35 1 designates the top cover of a loose leaf binder, said cover having secured thereto at one end the usual base plate 2. Mounted on said base plate, and secured by screws 3, is a housing 4. Formed in the top and side of said housing is a pair of recesses 5. Aligning with said recesses is another pair of recesses 6 formed in the base plate 2. These recesses 5 and 6 are for the reception of a 40 45 pair of binder posts 7, which are secured to the base plate 8 of the bottom cover 9 of the binder.

Pivotedly mounted on pivots 10 to the under side of the top wall of the housing 4 is 50 a pair of swinging blocks 11, one end of each block being located adjacent the end of each recess 5. Formed in each block, at one end, is a tapering ball seat 12. Each seat has movably mounted therein a ball 13.

55 Reciprocably mounted on the under side

of the top wall of the housing 4 is a plate 14. Said plate is held in sliding relation to said wall by a stud 15 formed on a button 16. Said stud is secured to said plate 14, and is mounted in the slot 17 formed in the top 60 wall of said housing. Formed in said plate 14 adjacent each end is a binder post engaging recess 18, and leading from each recess is an inclined surface 19. Leading from each inclined surface 19 is an inclined surface 20, said surfaces 20 being inclined oppositely to the surfaces 19. Formed in said plate 14 is a cut-away portion 21 in which is mounted a coil spring 22. One end of said spring is adapted to bear against said plate 65 14, and the other end against a depending portion 23 formed from the top wall of the housing 4.

In the operation of this improved device, when it is desired to secure the top cover 1 75 to the binder posts 7 as shown in Fig. 2, said posts are engaged by the recesses 5 and 6, the reciprocating plate, of course, being previously moved to one side, as shown, by the engagement of the posts 7 against the inclined surfaces 26 of the plate 14. It is to be noted that the position of the posts 7 is in approximate alinement with the pivots 10 of the blocks 11.

The spring 22, bearing against the plate 85 14 and depending portion 23 of the housing 4, will move said plate until the recesses 18 engage the posts 7. During this direction of movement of said plate 14, the inclined engaging portions 24 of each 90 block 11 will be engaged by the inclined surfaces 18. As said portions 24 ride on said surfaces, the blocks 11 are turned and the balls 13 are moved into approximate alinement with said posts 7 and pivots 10. As 95 the loose leaves A, which have been mounted on the posts 7, have a tendency toward giving an upward pressure to the top cover 1, the balls 13 will travel downwardly in their respective tapering seats 12, thus gripping the posts 7 securely (as shown in Fig. 3) through the opening 27 formed in each tapering seat 12.

In removing the top cover 1, when the plate 13 is moved in the opposite direction 105 by engaging the button 16 of the stud 15, the angular engaging portion 25 of each block 11 will ride on each inclined surface 20 of said plate 14, thus causing the blocks 11 to turn on their respective pivots 10 so the 110

balls 13 will be moved outwardly from the posts 7.

What I claim is:

1. A clutch comprising a binder member, a post to be engaged by said member, a pivotally mounted block carried by said member adapted to swing transversely of said post, and a ball carried by said block adapted to engage and grip said post.
- 10 2. In a loose leaf binder, posts therefor, a binder member for engagement with said posts, swinging blocks carried by said member, a tapering seat formed in each of said blocks, a ball located in each seat, and means for swinging said blocks so said balls will engage said posts.
- 20 3. In a loose leaf binder, a pair of posts, a binder member for engagement with said posts, a pair of swinging blocks secured to said member, a tapering seat formed in one end of each of said blocks, a ball located in each of said seats, each of said balls adapted to protrude from their respective seats, and means for swinging said blocks so said balls will engage said posts.
- 30 4. In a loose leaf binder, a post support, a post mounted on said support, a binder member adapted to be mounted on said post, a locking element comprising a swinging block having a ball seated therein carried by said member, and a reciprocating plate having inclined surfaces formed thereon adapted to swing said block toward and away from said post so that said ball will engage and disengage said post.
- 40 5. In a loose leaf binder, posts therefor, a binder member for engagement with said posts, a locking element comprising a pair of swinging blocks each having a tapering seat formed therein, a ball located in each seat adapted to protrude therefrom, a reciprocating plate having inclined faces formed thereon, one pair of said inclined faces adapted to move said blocks toward said posts, and another pair of said inclined faces adapted to move said blocks from said posts so said balls will engage and disengage said posts.
- 50 6. In a loose leaf binder, a pair of posts, a binder member adapted to be mounted on said posts, a reciprocating plate, with a pair of oppositely inclined faces formed adjacent each end of said plate, a pair of pivotally mounted blocks adapted to be operated on by said inclined faces, a tapering seat formed in each of said blocks, a ball carried by each of said seats, said balls adapted to be engaged against said posts, when said blocks are engaged by one of each of said pairs of inclined faces of said plate when said plate is moved in one direction, said balls adapted to be disengaged

from said posts when said blocks are engaged by the others of said inclined faces when said plate is moved in the opposite direction.

7. In a loose leaf binder, a pair of posts, a binder member adapted to be mounted on said posts, a reciprocating plate with an inclined surface formed on said plate adjacent each end thereof, having the same inclination, and another inclined surface formed on said plate adjacent each end but inclined oppositely to said first mentioned surfaces, said plate also having a recess formed therein adjacent each end, a pair of pivotally mounted blocks having tapering seats formed therein located adjacent said plate, a ball located in said seat, one pair of said surfaces having the same inclination adapted to engage one end of said blocks when said plate is moved in one direction, the other pair of said surfaces adapted to engage the other end of said blocks when said plate is moved in an opposite direction, said surfaces forming means of engaging and disengaging said balls to and from a pair of binder posts when said plate is reciprocated, said recesses adapted to engage said posts simultaneously with said balls.

8. In a locking device a binder member, a post to be engaged by said member, a pivotally mounted block carried by said member adapted to swing transversely of said post, a ball carried by said block adapted to engage said post, and a reciprocably mounted member for actuating said block.

9. A loose leaf binder comprising posts, a binder member for said posts, pivotally mounted blocks thereon adapted to swing transversely of said posts, and a reciprocably mounted plate adapted to actuate said blocks.

10. A loose leaf binder comprising posts, a binder member for said posts, pivotally mounted blocks thereon adapted to swing transversely of said posts, a reciprocably mounted plate adapted to actuate said blocks, and a ball carried by each of said blocks adapted to engage said posts.

11. In a locking device, a post, a binder member for engagement with said post, a swingingly mounted block carried by said member, a ball carried by said block, and a reciprocably mounted plate for actuating said block, said plate when moved in one direction adapted to engage and move one end of said block, and when moved in the opposite direction adapted to engage and move the opposite end of said block.

THOMAS E. HEETER.

In the presence of—

M. C. HAMMON,

H. G. FLETCHER.
